UNITED STATES PATENT OFFICE.

FRANK P. MILLER, OF MEADVILLE, PENNSYLVANIA.

CUTTING-TOOL.

1,358,013.

Specification of Letters Patent.

Patented Nov. 9, 1920.

Application filed March 31, 1919. Serial No. 286,284.

To all whom it may concern:

Be it known that I, FRANK P. MILLER, a citizen of the United States, residing at Meadville, in the county of Crawford and State of Pennsylvania, have invented new and useful Improvements in Cutting-Tools, of which the following is a specification.

This invention relates to cutting tools and consists in certain improvements in the construction thereof as will be hereinafter fully described and pointed out in the claims.

More particularly the invention relates to that type of tools, commonly used as milling cutters and comprises a carrier, or head, with inserted blades. In some respects this invention is an improvement over the construction shown in my former Patent, #1,244,227, dated Oct. 23, 1917.

The invention is illustrated in the accompanying drawings as follows:

Figure 1 is a side elevation of the cutter, partly in section on the line 1—1 in Fig. 2, the blades being here arranged for face milling.

Fig. 2 shows an end view of the cutter shown in Fig. 1.

Fig. 3 a side elevation, partly in section of the cutter head involving the principles of my invention arranged for slabbing.

Fig. 4 a side elevation of one of the cutting blades.

Fig. 5 an elevation of the fillet.

Figs. 6 and 7 elevations of the wedge member.

1 marks the carrier, or head. This is provided with the longitudinally or axially arranged groove 2 in which are arranged the cutting blades 3. A groove 4 is provided along one wall of the groove 2 and a socket 5 is provided in the face of the cutting blade adjacent the groove 4. A fillet 6 is placed in the socket 5 and when so placed can be inserted in the groove 4 as the cutter is slid into the cutter holding groove 2, the groove 4 extending through the end of the cutter head for this purpose.

A radially arranged and cylindrically shaped socket 7 is provided adjacent to the cutter groove 2 and passes through the bottom of the groove 4. A wedge member 8 is slidably mounted in this socket 7 and has a wedge surface 9 engaging the fillet 6. The wedge surface 9 is preferably serrated and engages serrations 10 in the fillet 6, the effect

of which is to lock the fillet against endwise movement in the groove 4. The fillet is preferably of the same length as the socket 5 in the cutter blade and consequently the fillet is locked against endwise movement in the cutter. The outer end of the 55 socket 7 is screw-threaded and a screw 11 is screwed into the socket against the wedge member 8. The groove 4 is slightly larger in radial direction than the fillet so that the fillet is free to move downwardly as well as 60 inwardly under the thrust of the wedge. From this it will be observed that the thrust on the cutter not only forces the cutter against the side wall of the groove 2 but also inwardly toward the bottom of the 65 groove. The bottoms of the grooves or slots 2 are inclined in the usual manner so that the cutters may be adjusted with relation to the diameter of the cutter as a whole. It 70 will be observed that the wedge member 8 is in the form of a cylindrical plug fitting the socket 7, one face of the plug being cut away to give the wedge surface 9. This wedge surface, therefore, extends some distance along the fillet and at the same time 75 there is a smooth sliding fit between the member 8 and the wall of the socket. In some respects the wedge member separate from the screw is an improvement over my former structure and while I prefer to provide the 80 interlocking feature involving the serrated wedge face and the serrations on the fillet when considered with relation to the broader phases of my invention this may be omitted.

In the preferred construction shown in Figs. 1 and 2 there is a screw-threaded socket having its axis centrally located in the cutter holding groove 2, this socket extending from the rear face of the carrier or head. A screw 12 is placed in these screw 95 threads and engages the rear end of the cutting blade. The cutting blade is preferably notched at 13 and the screw preferably has a conical end 14 so that the screw not only locks the cutting blade against endwise movement but also exerts thrust on the cutter forcing it into more intimate engagement with the bottom of the groove.

In the construction shown in Fig. 3 the head is arranged for a slabbing mill. In 105 it the screw 12 is omitted and instead of one wedge member 8 there are two wedge members operating on the fillet. The number

of wedge members may be varied from one to several as desired depending on the class of work for which the cutter is designed.

What I claim as new is:—

5. 1. In a cutting tool, the combination of a carrier having a cutter holding groove therein; a cutter arranged in the groove; a fillet operating against the cutter, said fillet permitting an endwise adjustment of the blade in the groove; a wedge member operating against the fillet, said wedge member having a face extending along the fillet; and means for exerting pressure against the wedge member.
10. 2. In a cutting tool, the combination of a carrier having a cutter groove therein and a wedge socket adjacent to the groove; a cutter in the groove; a fillet operating against the side of the cutter and insertible with the cutter endwise of the groove; a wedge member slidably but non-rotatively mounted in the socket and operating against the fillet; and means for exerting pressure on the wedge member.
15. 3. In a cutting tool, the combination of a carrier having a cutter groove therein and a wedge socket adjacent to the groove; a cutter in the groove; a fillet operating against the side of the cutter; a wedge member mounted in the socket and operating against the fillet; and a screw operating in the outer end of the socket against the wedge member.
20. 4. In a cutting tool, the combination of a carrier having a cutter holding groove therein; a cutter arranged in the groove; a locking member interlocking with the cutter and slidable with the cutter endwise into the groove; and means for locking said member with the carrier.
25. 5. In a cutting tool, the combination of a carrier having a cutter holding groove therein; a cutter arranged in the groove; a locking member interlocking with the cutter and slidable with the cutter endwise into the groove; and means for locking said member with the carrier and exerting pressure on the cutter through the member.
30. 6. In a cutting tool, the combination of a carrier having a cutter holding groove therein; a cutter arranged in the groove; a fillet arranged in the side of the cutter and interlocking therewith, said fillet having serrations therein; and means on the carrier exerting pressure on the fillet and co-acting with the serrations for locking the fillet and the cutter against endwise movement in the groove.
35. 7. In a cutting tool, the combination of a carrier having a cutter holding groove therein; a cutter mounted in the groove; a fillet operating against the side of the cutter, said fillet having serrations therein; a wedge member acting against the fillet, exerting pressure on the cutter through the fillet and
40. interlocking with the serrations to lock the fillet against endwise movement.
45. 8. In a cutting tool, the combination of a carrier having a cutter holding groove therein and a fillet holding groove in the side wall of the cutter holding groove and a radially extending socket leading into the fillet holding groove; a cutter arranged in the groove, the cutter having a socket in a side thereof; a fillet arranged in the socket, the fillet being co-extensive in length with the socket, said fillet having serrations thereon; a wedge member slidably mounted in the radially extending socket, said wedge member having serrations on the wedge face engaging the serrations on the fillet; and a screw arranged in the outer end of the radially arranged socket exerting pressure on the wedge member.
50. 9. In a cutting tool, the combination of a carrier having a cutter holding groove therein and a screw threaded socket extending lengthwise of the groove; a cutter arranged in the groove; and a screw in the socket, said screw and cutter having inclined engaging surfaces tending to exert pressure upon the cutter in an inward direction.
55. 10. In a cutting tool, the combination of a carrier having a cutter holding groove therein and a screw socket extending lengthwise of the groove and having its axis within the groove; and a screw in the socket engaging the end of the cutter.
60. 11. In a cutting tool, the combination of a carrier having a cutter holding groove therein and a screw threaded socket extending lengthwise of the groove; a cutter arranged in the groove; a screw in the socket, said screw and cutter having inclined engaging surfaces tending to exert pressure upon the cutter in an inward direction; and means acting on the cutter intermediate of its ends for clamping the cutter in the groove.
65. 12. In a cutting tool, the combination of a carrier having a cutter holding groove therein and a screw socket extending lengthwise of the groove and having its axis within the groove; a screw in the socket engaging the end of the cutter; and means acting on the cutter intermediate of its ends for clamping the cutter in the groove.
70. 13. In a cutting tool, the combination of a carrier having a cutter holding groove and a screw socket extending lengthwise of the groove; a cutter arranged in the groove; a fillet arranged on the side of the cutter; a wedge member operating against the fillet; and a screw in the socket engaging the end of the cutter, said screw and the end of the cutter having inclined engaging surfaces.
75. 14. In testimony whereof I have hereunto set my hand.

FRANK P. MILLER.
